UNITED STATES PATENT OFFICE.

FREDERIC T. RUSSELL, OF GARDNER, MASSACHUSETTS, ASSIGNOR TO THE BLOUNT MANUFACTURING COMPANY, OF SAME PLACE.

DOOR CHECK AND CLOSER.

SPECIFICATION forming part of Letters Patent No. 598,010, dated January 25, 1898.

Application filed September 12, 1896. Serial No. 605,553. (No model.)

To all whom it may concern:

Be it known that I, FREDERIC T. RUSSELL, of Gardner, in the county of Worcester and State of Massachusetts, have invented certain new and useful Improvements in Door Checks and Closers, of which the following is a specification.

This invention has relation to means for automatically closing doors and so checking the momentum of the same as to prevent slamming, and has relation more particularly to that class of devices typified by the door-check Letters Patent No. 528,321, granted to Eugene I. Blount on the 30th day of October, 1894, to which Letters Patent reference may be had for a clear understanding of those features of the device shown on the accompanying drawings which are not hereinafter described in detail.

It is the object of the invention to provide a door-check which will not only operate to close the doors automatically and noiselessly, but which will likewise hold the doors open when they have been once swung, so as to lie at a predetermined angle relatively to the door-frame. At the present time whenever it is desired to keep open a door which is equipped with a door-check it is generally necessary to employ some additional means to bear against the door, such as a wedge forced under the lower edge of the same or a weight placed in front of it. Hence I desire, as before stated, to hold the door in an open position by means coöperating with the closing and checking devices.

To these ends my invention consists of a door closing and checking device provided with means for holding the door open when it has been swung into a predetermined position, all as I shall now proceed to describe in detail and then set forth in the claims hereto annexed.

Reference is to be had to the accompanying drawings, forming a part of this specification, in which like characters indicate like parts or features, as the case may be, wherever they occur.

Of the drawings, Figure 1 is a front elevation of a portion of a door and its casing, said door being equipped with one embodiment of my invention. Figs. 2 and 3 are

plan views of the door in a closed and an opened position, respectively. Fig. 4 is an enlarged end elevation of the device chosen for the purpose of illustrating my invention. 55 Fig. 5 is an enlarged section on the line 5 5 of Fig. 2 of the lower portion of the door closing and checking device equipped with my invention. Fig. 5^a is a section on the line 5^a 5^a, Fig. 5. Fig. 6 is an enlarged horizontal section through the fluid - cylinder, taken on the line 6 6 of Fig. 1. Fig. 7 is a similar section illustrating the parts as being in a position to hold the door open. Fig. 8 is a vertical longitudinal section showing a 65 slightly-different embodiment of my invention. Fig. 9 is a section on the line 9 9 of Fig. 8.

The device which is shown on the drawings and which I am about to describe is merely one embodiment of my invention, and it will be understood that I am in no wise limited to the details of construction thereof, since the invention may be likewise embodied in various devices of other shapes or constructions.

Referring to the drawings, *a* designates the door, and *b* the door frame or casing, to which the door is hinged at *c*. To the door-frame is attached a bracket *d*, having projecting lugs *e*, with socketed inner faces for the reception of the ball-like end *f* of the arm *g*, which latter has a ball-and-socket connection with an arm *h*, said arm *g* being formed in two parts adjustably connected together.

i is a casing secured to the door and in 85 which are inclosed the ordinary spring-receiving chamber and the cylindrical chamber for the liquid. The spring *j* has one end connected to the shaft *k* and the other to the casing or spring-barrel, so that when the door 90 is opened it will, through the medium of the arm *h*, which is attached to the shaft *k*, and the arm *g*, close it as soon as the door is allowed to swing freely. The shaft is provided with a crank *l*, connected by a link *w* with a 95 piston *m*, adapted to slide back and forth in the cylindrical portion of the casing.

The casing is provided with ducts and valves, whereby when the door is opened the liquid in the cylinder may flow freely behind 100 the piston through an enlarged aperture and will have to pass through a restricted aper-

ture when the door is closing, whereby the momentum of the latter is retarded and checked.

Thus far the device is no different from the door-check illustrated and described in the patent to E. I. Blount before referred to, and to which reference may be had for a full and clear understanding of all the matters of detail in the construction and mode of operation 10 of the device.

I shall now proceed to describe my invention, which may be employed in connection with the above-described mechanisms, for holding the door in an open position, but 15 which may also be used in connection with other devices as well.

The end of the cylinder is provided with a cap *n*, through which a screw *o* is threaded, said screw passing through a suitable stuffing-box secured to the cap and having a head *p*. The inner end of the screw is provided with or formed into a pin, on which is secured a frusto-conical disk *q* by upsetting the metal of the pin. The disk might be described as 25 having a beveled edge *r* and may be secured to the screw in any other desired way, it and the screw constituting an abutment.

To the end of the piston *m*, which is apertured, is secured a split ring *s*, having a beveled inner edge *t* corresponding to the beveled edge of the disk *q*, said ring being slightly smaller in internal diameter than the diameter of the said disk and constituting a spring to grasp the latter, for a purpose to be set 35 forth. The ring is held against the end of the piston by pins *u*, passing through enlarged apertures *v* therein, so that the ends thereof may be separated, while at the same time it is secured firmly to the piston.

40 It will be observed from Figs. 2, 3, 6, and 7 that when the door is opened at about an angle of ninety degrees the shaft *k* has been given one-half of a rotation, so that the crank has moved through an arc of about one hundred and eighty degrees. This has caused the piston to be moved to the other end of the cylinder. Hence when the abutment has been properly adjusted on opening the door through an arc of ninety degrees until the 45 parts assume the positions illustrated in Figs. 3 and 7 the pivot-pin *l*' will have moved slightly past a dead-center with the pivot-pin *w*' and the shaft *k* or crank *l*, as shown in dotted lines in Fig. 7, and upon letting the 50 door partially and slowly close until the two pivot-pins *l*' and *w*' and the axis of the crank are almost at a dead-center, as shown in full lines in said last-mentioned figure, the spring *s* engages the abutment and holds the piston 55 against being returned to its original position, since they neutralize the action of the door-closing spring *j*, whereupon the door will remain at rest. The spring *s* and the abutment hold the link and crank from being moved 60 past a dead-center unless considerable force be employed to close the door. Immediately, however, upon moving the door but a very

small distance until the parts are past a dead-center and the spring or split ring is free from the disk the spring *j* will cause the rotation of the shaft *k* and the closing of the door.

In Figs. 8 and 9 I employ a curved spring *s'* in place of the split ring or spring *s* and am able to dispense with the beveled disk. 75 In this event the spring *s'* bears directly against an abutment formed by the pin *t* on the end of the screw with sufficient force to hold the parts just beyond a dead-center and prevent the door from closing. The spring *s'* is provided with slots *u'* to receive screws *v*, by which it is secured to the piston.

It will be understood that the spring and abutment might be reversed—that is to say, the spring could as well be secured to the end 85 wall or cap of the cylinder and the abutment be secured to the end of the piston—and hence I do not limit myself to the exact position of either.

It may be here stated that the crank moves 90 through an arc of one hundred and eighty degrees when the door has been opened about ninety degrees and that the further movement of the door toward open position causes the further rotation of the crank-shaft and a reverse movement of the piston, so that as soon as the door is released the door-closing spring causes the reverse rotation of the crank and the closing of the door unless the abutment and the spring *s* are allowed to be slowly engaged. If, however, the door gains considerable momentum in closing, the abutment and spring *s* will not neutralize it and the door will be closed.

Having thus explained the nature of my invention and described a way of constructing and using the same, although without attempting to set forth all the ways in which it may be made or all the modes of its use, I declare that what I claim is—

1. In a door-checking device, the combination with door-closing means, mechanism for checking the momentum of the door-closing movement of the door, and a casing for inclosing the first-mentioned elements, of an abutment on the casing, and a spring mounted on the checking mechanism and coacting with the abutment, for holding the door-closing means against movement.

2. In a door-checking device, the combination with a door-closing spring, and a piston located in a cylinder and connected with the spring, of an abutment and a spring, one of the two elements last mentioned being connected with the piston and the other being arranged in its path, for holding the closing-spring against movement.

3. In a door-checking device, the combination with a door-closing spring, a shaft operated by the spring, a crank on the shaft and a piston operatively connected with the crank, of a yielding stop constructed and arranged to permit the crank to revolve past the center line of its connection with the piston, and

hold it there against the force of the door-closing spring.

4. In a door-closing device, in combination, a door-closing spring, a crank operated by the spring, and mechanism for temporarily holding the crank against the impulse of the spring and thereby preventing the same from closing the door until the crank is released.

In testimony whereof I have signed my name to this specification, in the presence of ¹⁰ two subscribing witnesses, this 29th day of August, A. D. 1896.

FREDERIC T. RUSSELL.
